UNITED STATES PATENT OFFICE.

HARRY ST. G. TUCKER, OF WEST RALEIGH, NORTH CAROLINA.

PIPE-WRENCH.

1,024,043.

Specification of Letters Patent.

Patented Apr. 23, 1912.

Application filed September 25, 1911. Serial No. 651,180.

To all whom it may concern:

Be it known that I, HARRY ST. G. TUCKER, a citizen of the United States, residing at West Raleigh, in the county of Wake and 5 State of North Carolina, have invented certain new and useful Improvements in Pipe-Wrenches, of which the following is a specification.

The object of my invention is to provide 10 a pipe wrench of simple and cheap construction and which shall possess a quick and firm gripping action with a powerful leverage and which shall be conveniently handled and be quickly applied and released.

15 It relates to that form of pipe wrench in which two crossed jaw levers are fulcrumed upon a connecting pin or rivet and which jaw levers on one side of their fulcrum are serrated upon their adjacent faces and, on 20 the other side of the fulcrum have their shank ends connected as follows, one end pivoted directly to a long-handled operating lever and the other end to a link which in turn is pivotally connected to the handle 25 lever, there being a spring to hold the jaws in normal gripping relation.

30 My invention consists in a new and improved construction and arrangement of pipe wrench of the general type described, whereby the objects of my invention are attained in a simple and practical way, as will be hereinafter more fully described with reference to the drawing, in which—

Figure 1. is a side view of my improved 35 pipe wrench in its normal position of rest and showing in dotted lines the movement of the parts in opening the jaws to apply them to the pipe, and Fig. 2. is a fragmental view showing a slight modification 40 of the jaws.

In the drawing A, A¹ and B, B¹ are 45 two crossed jaw levers of substantially the same shape, which are pivotally connected in the middle to each other by means of a fulcrum pin or rivet 1. The free ends of these jaw levers are fashioned into gripping jaws A, B, whose inner opposite faces are serrated with teeth, the inclination of the teeth on one jaw being reverse to the 50 inclination of those on the other, so as to cause them to bite into the smooth periphery of the pipe when turned in the direction of the circular arrow. The rear or shank members A¹ B¹ of the jaw levers are extended 55 substantially parallel to each other, but the one B¹ is made considerably shorter than

the other one A¹. To the end of this shorter shank is pivoted directly the end of a long handle-lever C, the connection being made a loose one by a fulcrum pin or rivet 2 which permits a free flexion of the joint. To the end of the other and longer shank A¹ is pivotally connected a transverse link bar D. This link bar is connected at one end to the shank A¹ by a fulcrum pin or rivet 4, while 60 its other end is similarly connected at 3 to the long handle-lever C. This connection at 3 is made a short but invariable distance away from the end of the short shank B¹ so that the link bar D normally stands at 65 70 or about at right angles to the long handle-lever C and the shank ends A¹ B¹, while the handle-lever C is substantially in alinement with the shank B¹.

At a point on the shank A¹ between the 75 jaw fulcrum 1 and the link pivot 4 is anchored a flat spring E. This is secured at one end to the jaw shank A¹ by being curled around a screw 6 firmly set into the side of the shank and is held by a back stop screw 80 or lug 5, so that the free end bears against the inner edge of the link bar D at a point about opposite the fulcrum pin 3 connecting the link bar and the handle-lever. The tendency of the spring is to throw the fulcrum 85 90 95 100 105 110 3 away from fulcrum 2 and draw the fulcrum 2 toward fulcrum 4 in seeking to establish a straight line between the centers 1, 2, 3, and thus causes the jaws A B to have a normal initial grip from the action of said spring, so as to instantly fasten the serrated jaws upon the pipe. The relative lengths of the shanks A¹ B¹ and their connection with and relation to the handle lever and link bar are highly important, as is also the position and cooperative relation of the spring. By making the lever shank B¹ shorter than A¹ the normal position of the handle lever C is one in alinement with said shank B¹ which makes the tool a straight tool capable of being operated to much greater advantage and with a greater power of leverage since the joint 2 becomes the center of a toggle 1, 2, 3. By making the shank B¹ shorter than A¹ also the gripping spring E is arranged in transverse relation to the tool and is completely housed and protected against accidental abrasion, dislocation and breakage, for it extends inwardly from its point of anchorage and lies in the plane of the link bar D along its edge and in the recess left between the ends of the

link bar and the end of the shank B¹. Furthermore the position and action of this spring makes a more efficient straightening of the centers 1, 2, 3, and a more sensitive initial grip on the pipe. It will also be seen that the handle-lever, C, lies in the same plane as the longer shank end, A¹, and this permits the handle lever C, to stop against the end of the shank, A¹, when the handle lever is deflected to its extreme position, as indicated in dotted lines, and this prevents the handle lever from being doubled around into an inconvenient position and limits its range of movement.

In carrying out my invention I would have it understood that the form and construction of the terminal jaws A B is unimportant. They may be of the form shown in Fig. 1, or may be of the alligator pattern shown in Fig. 2, or may take any other shape without departing from the principle of my invention. Another advantage of my pipe wrench is its great cheapness. It will be seen that all of the parts of the wrench may be cheaply stamped out of plate metal of uniform thickness and after the finishing of the gripping jaws the parts are loosely riveted together in a very cheap and expeditious way, to form an extremely simple and practical tool.

I claim.

1. A tool of the kind described, comprising two crossed jaw members fulcrumed to each other in the middle and having their shank ends extended substantially parallel to each other and made of different lengths, a relatively long handle lever pivotally connected directly to the end of the shorter shank and in substantial alinement therewith, a transverse link bar pivotally connected at one end to the end of the longer shank, and pivotally connected at the other end to the handle lever at a point beyond the lever's connection with the short shank, said handle lever and longer shank being

in the same plane to cause the end of the longer shank to act as a stop to the handle lever.

2. A tool of the kind described, comprising two crossed jaw members fulcrumed to each other in the middle and having their shank ends extended substantially parallel to each other and made of different lengths, a relatively long handle-lever pivotally connected directly to the end of the shorter shank and in substantial alinement therewith, a transverse link bar pivotally connected at one end to the end of the longer shank and pivotally connected at the other end to the handle lever at a point beyond the lever's connection with the short shank to form a normally straight tool and a spring connected to the longer shank member and extending inwardly in transverse relation to the tool and bearing outwardly against the link bar and lying within the plane of the same between the link bar and the end of the short shank and housed and protected thereby.

3. A tool of the kind described, comprising two crossed jaw members fulcrumed to each other in the middle and having their shank ends made of different lengths, a relatively long handle lever pivotally connected directly to the end of the shorter shank, a transverse link bar pivotally connected at one end to the end of the longer shank and pivotally connected at the other end to the handle lever at a point beyond the lever's connection with the short shank, and a spring arranged within the space bounded by the jaw shanks and link bar and adapted to close the jaws.

In testimony whereof I affix my signature in presence of two witnesses.

HARRY ST. G. TUCKER.
